HEAD COVERING FOR THE PROTECTION OF CURLS

Elaine Baker Welch, New York, N. Y.

Application May 17, 1954, Serial No. 430,107

5 Claims. (Cl. 132—46)

This invention relates to a head covering for the protection of curls.

One object of the present invention is the provision of a cap positionable on the wearer's head for retaining hair curls in shape and for protecting them against disarrangement.

Another object of the present invention is the provision of a curl protecting cap which is especially adapted to be worn by women while sleeping to thereby afford protection to their curls which would ordinarily become completely disarranged while sleeping.

Yet another object of the present invention is the provision of a generally improved curl protecting cap of the above character which is of simple design and construction, economical to manufacture, and which is highly efficient in the accomplishment of its intended purpose.

The above and other objects, features and advantages of the present invention will be more fully understood from the following description considered in connection with the accompanying illustrative drawing.

In the drawing:

Fig. 1 is a side view of the curl protecting cap shown positioned on the wearer's head, with a portion of the cap broken away to reveal structural details;

Fig. 2 is a perspective view of the curl protecting cap;

Fig. 3 is a sectional view, on an enlarged scale, taken on line 3—3 of Fig. 2 showing a curl positioned in one of the curl holders; and

Fig. 4 is a view similar to Fig. 3 showing a modified form of curl holder.

Referring to the drawing in detail, the curl protecting cap 10 is of a size and shape generally corresponding to the contour of a person's head 12 with said cap being provided with a plurality of resilient curl receiving elements 14 disposed in the interior of said cap and secured thereto. The cap 10 may be formed of any suitable material, for example flexible and resilient sheet material which may be readily expanded for positioning on the wearer's head.

Pursuant to the present invention, each of the curl receiving elements 14 is formed of a relatively soft flexible and resilient material such as foam or sponge rubber, and is provided with a central aperture or bore 16 adapted for the reception of the free end portion 17 of an associated curl 19 for maintaining the latter in a curled condition. Each of the apertures 16 is closed at the bottom thereof by portions of the cap whereby said apertures are open at their inner or receiving ends only. Each of the curl receiving elements 14 may be secured to the interior of cap 10 in any suitable manner as by means of a cementing operation. The elements 14 are spaced in the interior of the cap 10 at desired intervals and each of said elements is provided with a tapered free end portion 20 of arcuate configuration.

The cap 10 and the curl protecting elements 14 are preferably formed of flexible and resilient material in order to comfort the wearer while protecting her curls. It will be understood that curls positioned in the curl

2

receiving members 14 will maintain their shape even though pressure is exerted against the head 12 such as when the head is reposing on a pillow.

At the lower marginal edge of the head covering 10 is an elastic band 24 suitably integrated therewith for yieldably maintaining said covering on the wearer's head with the covering enclosing the wearer's hair. In practice, the cap 10 is positioned on the wearer's head and the free end portions 17 of curls 19 are manipulated into the apertures 16 of elements 14, it being understood that said cap may be expanded sufficiently to permit the wearer's hand to be inserted between the cap and hair to effect such manipulation. Each curl will be associated with an adjacent element 14 and the particular wearer need not utilize all of the elements 14 provided in the cap.

With reference to Fig. 4, there is shown a slightly modified form of the present invention in which the elements 14' have a planar face part 20' at the inner free end with said elements being otherwise structurally and functionally similar to elements 14. Thus when the cap 10 is positioned on the wearer's head, the elements 14 will abut the wearer's hair and will be spaced to normally accommodate all of the wearer's curls to protect the latter against disarrangement consistent with the wearer's comfort, notwithstanding the tendency towards curl disarrangement normally encountered while the wearer is reposing on a pillow, as when sleeping. Since curl receiving elements 14 are of sponge rubber or similar material, the free end portion 17 of curls 19 may be facilely positioned within the central apertures or bores 16.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent is:

1. A head covering for the protection of curls, comprising a flexible and resiliently expandable cap adapted to be positioned on the wearer's head for enclosing the wearer's hair, said cap having secured thereto on the inside thereof a plurality of spaced curl receiving elements formed of flexible material, each of said elements having a closed bottom aperture adapted for the reception of a free end portion of associated curl for maintaining the latter in a curled condition when the cap is positioned on the wearer's head.

2. A head covering for the protection of curls, comprising a flexible and resiliently expandable cap adapted to be positioned on the wearer's head for enclosing the wearer's hair, said cap having secured thereto on the inside thereof a plurality of spaced curl receiving elements formed of flexible material, each of said elements having a closed bottom aperture adapted for the reception of a free end portion of associated curl for maintaining the latter in a curled condition when the cap is positioned on the wearer's head, each of said elements projecting inwardly of said cap and having a tapered free end portion adapted to abut the wearer's hair.

3. A head covering for the protection of curls, comprising a flexible and resiliently expandable cap adapted to be positioned on the wearer's head for enclosing the wearer's hair, said cap having secured thereto on the inside thereof a plurality of spaced curl receiving elements formed of flexible material, each of said elements having a closed bottom aperture adapted for the reception of a free end portion of associated curl for maintaining the latter in a curled condition when the cap is positioned on the wearer's head, each of said elements projecting inwardly of said cap and having a free end provided with a planar face adapted to abut the wearer's hair.

4. A head covering for the protection of curls, comprising a flexible and resiliently expandable cap adapted to be positioned on the wearer's head for enclosing the wearer's hair, said cap having secured thereto on the inside thereof a plurality of spaced curl receiving elements formed of flexible material, each of said elements having a closed bottom aperture adapted for the reception of a free end portion of associated curl for maintaining the latter in a curled condition when the cap is positioned on the wearer's head, each of said elements projecting inwardly of said cap and having a free end provided with a planar face adapted to abut the wearer's hair.

4. A head covering for the protection of curls, comprising a flexible and resiliently expansible cap adapted to be positioned on the wearer's head for enclosing the wearer's hair, said cap having secured thereto on the inside thereof a plurality of spaced curl receiving elements formed of flexible material, each of said elements having a closed bottom aperture adapted for the reception of a free end portion of associated curl for maintaining the latter in a curled condition when the cap is positioned on the wearer's head, said cap being formed of sheet material and each of said elements being formed of sponge or foam rubber.

5. A head covering for the protection of curls, comprising a flexible and resiliently expansible cap formed of sheet material adapted to be worn on the wearer's head for enclosing the wearer's hair, said cap having secured thereto on the inside thereof a plurality of spaced curl receiving elements formed of foam or sponge rub-

ber, each of said elements projecting inwardly of said cap into abutting relation with the wearer's hair when the cap is worn, each of said elements having a pocket closed at its outer end and open at its inner end for the reception of a free end portion of an associated curl for maintaining the latter in a curled condition when the cap is worn on the wearer's head.
